UNITED STATES PATENT OFFICE.

ROBERT L. WILLIAMS, OF NEWTON, MASSACHUSETTS, ASSIGNOR TO SUBMARINE SIGNAL COMPANY, OF PORTLAND, MAINE, A CORPORATION OF MAINE.

SUBMARINE SIGNALING.

Application filed April 25, 1918. Serial No. 230,802.

To all whom it may concern:

Be it known that I, ROBERT L. WILLIAMS, of Newton, in the county of Middlesex and State of Massachusetts, a citizen of the 5 United States, have invented a new and useful Improvement in Submarine Signaling, of which the following is a specification.

In a submarine signaling receiver a diaphragm located in a ship skin receives sound 10 waves from various directions and transmits them by means of a microphone or the like to a suitable receiving instrument or indicator. To receive sounds coming from a single direction only it is desirable that so far 15 as practicable the undesired sound waves, that is, those coming from a different direction, be eliminated, leaving the microphone free to receive and transmit only sound waves coming from the desired direction 20 and eliminating undesired vibrations by interference.

I have shown in the drawings and describe below several means for this purpose all based upon the idea broadly speaking that 25 the desired sound waves shall arrive at the microphone in phase, while the undesired wave or waves arriving from undesired directions shall reach the microphone by various more or less opposed paths and out of 30 phase so that on coming to a common point of meeting they will interfere and so neutralize or more or less kill each other.

In the drawings I have shown various ways of carrying out my invention, all involving, however, the same principle. Other 35 embodiments will occur to those skilled in the art.

Figure 1 is a horizontal section of a portion of a ship having my mechanism attached 40 thereto.

Fig. 2 shows in section a portable form of my invention which is watertight and may be utilized in a water ballast tank or elsewhere, being suspended if desired so that it 45 may be rotated about a vertical axis to secure direction.

Fig. 3 is a vertical section showing the apparatus located in the bottom of the ship.

Fig. 4 is a similar section showing a modification.

Fig. 5 is a horizontal section showing a mounting of an apparatus similar in kind to that shown in Fig. 4.

Fig. 6 is a vertical section of a ship in 55 which a similar apparatus is mounted.

Fig. 7 shows in horizontal section another form of the device shown in Fig. 1 and is illustrative of a way of determining the proportions of the various parts to secure a desired result, and

Fig. 8 is a view showing a device in which a microphone is not used, the diaphragm being supplied with ear-pieces of the stethoscope type.

In all these views A is a skin or frame of 65 the ship. In each case also there is a microphone B located to receive the sound vibrations and transmit them by leads b to a suitable receiver or indicator (not shown). In addition there are a plurality of diaphragms C or other sections of the skin of 70 the ship especially adapted to receive the sound waves and suitably connected to the microphone B. I have shown two means of connecting the diaphragm with the microphone. In Figs. 1, 2, 3 and 7 the means is 75 a liquid confined in tubes leading from the diaphragms to the microphone, which is preferably suspended in an enlargement of the tube system. In Figs. 4, 5 and 6 the connections are preferably metallic—mainly wires, one end of each of which is attached 80 to a diaphragm in the ship's skin, while the other is connected directly or indirectly with a microphone, all as will be below described. 85

In Figs. 1, 2, 3 and 7, D is a casing, metallic or otherwise, of any suitable shape. This casing is attached to the interior of the ship and encloses a tube system. This system comprises an enclosure E forming a 90 chamber in which is mounted the microphone B in any suitable manner.

This chamber E has in each case tubular connections with openings in the ship's skin, each opening being closed by a diaphragm. 95 In Fig. 1 there are four such openings on each side of the ship and four diaphragms C, C¹, C² and C³, each closing one of said openings.

The chamber E has a tube or passage e 100 leading directly to the diaphragm C. There is a passage e¹ leading at right angles from the passage e from which proceed passages e², e³, e⁴. The chamber E and the various tubes or passages e, e¹, e², e³ and e⁴ are all 105 within the casing D, which is packed with a sound-insulating material F, such as felt. As shown in Fig. 1, two casings, each with its enclosures, are arranged one on each side of the ship and equidistant from the bow, 110

and are adapted to receive sound waves from substantially dead ahead.

It will be seen that sound waves coming from a distance and reaching the various 5 diaphragms will vibrate them and establish vibrations in the liquid in the various passages.

The location of the diaphragms and the 10 length of the tubes are such that the vibrations received by the diaphragm C^3 from a given direction will reach the junction of the passages e^1, e^3 in phase with the vibrations reaching the same point from the diaphragm C^2 . The vibrations arriving 15 from diaphragms C^1 and C will likewise join these said vibrations in phase, so that all will reach the microphone B in phase, and the result will be a clear reproduction of the vibrations to be listened for. Waves 20 coming from a point, say off the beam, will arrive at the several diaphragms in different phase, and hence vibrations differing in phase will enter and pass into and through the tubes to the microphone and not being 25 in phase will interfere, so that the microphone will not transmit such signals to the indicator.

The apparatus is especially arranged in Fig. 1 to receive sounds from nearly dead 30 ahead.

In Fig. 2 there is shown in horizontal section a portable apparatus which is intended to be supported by a strap or otherwise in the fore peak tank of the ship, the 35 means of suspension not being shown. The casing D is watertight; the diaphragms are lettered C, C^1, C^2 and C^3 as before, and each is connected by liquid-containing passages f with the chamber E containing the 40 microphone B . These passages are of equal length so that when the sound waves strike all four diaphragms in phase compressional waves in phase will pass in and be received and transmitted by the microphone to the 45 indicator. This will happen when the diaphragms are normal to the direction from which the sound waves arrive; when, however, the diaphragms are not normal to such direction, the sound waves will not be in 50 phase and hence at the various junctions of the passages f , will oppose or otherwise interfere with each other, thus neutralizing each other to a greater or less extent and reducing considerably the effect on the microphone. By turning the instrument about 55 a vertical axis the direction from which the incoming sound proceeds may be easily ascertained.

In Fig. 3 a similar apparatus is shown 60 in the bottom of the ship, its construction and mode of operation being in all respects as in the apparatus shown in Figs. 1 and 2. This apparatus is arranged for receiving sounds from ahead or astern but not on 65 the beam. The forms of my apparatus

shown in Figs. 4, 5 and 6 are similar in their theory of operation to the forms previously described. They differ chiefly in the substitution of a metallic path for the sound waves for the liquid path first above 70 described, with some details of construction below described.

Thus in Fig. 4 wires g connect the diaphragms C, C^1, C^2 and C^3 with an inboard diaphragm G , which is suitably mounted in one of the decks G^1 . As in the former case the length and arrangement of these wires are such that sounds from all the diaphragms C, C^1, C^2, C^3 will reach the microphone B in phase provided the sound 75 approaches the ship from ahead or astern.

In this case as in Fig. 6 the inbound diaphragm G carries a link g^1 pivoted to a bell crank g^2 mounted on a support g^3 on the deck G^1 . The upper arm of the bell crank 80 engages a rod or pin b^1 connected to one element of the microphone so that the vibrations of the diaphragm G will cause corresponding movements of the microphone.

In Fig. 6 but two diaphragms C, C^1 are 85 shown and they are connected to a light stiff compensating lever H suitably hung below the inboard diaphragm and connected thereto by the rod or wire h . Sounds reaching the two diaphragms C, C^1 simultaneously and in phase move the lever H similarly. If they are out of phase they rock the lever H , thereby only partly transmitting their energy to the button, a portion of the energy being lost by interference.

The arrangement of Fig. 5 is like that of Fig. 4 applied to the side of the ship. In this case, however, the microphones are each attached directly to a diaphragm g^2 .

I have shown in Fig. 7 the method of determining the proper lengths of sound passages. In this view, X being the source of sound, the dotted lines show the line of travel to C and C^1 . It will be noticed that the passage of the sound waves from X to the microphone B through the passage f is 90 substantially equal to that through the passage f^1 , so that the sound waves reaching the microphone through both passages will arrive at the microphone in phase. The same will be true of sound waves originating at X and traveling to B by the diaphragms C^2 and C^3 . Thus the sound waves traveling from X will all arrive at B 95 substantially in phase.

In Fig. 8 is shown an acoustic receiver based on the same principle but without electrical connections. The diaphragms C, C^1 in this case are connected by wires g 100 each with its own diaphragm J which is mounted to close one end of a casing J^1 , the rear end j of which is also closed to form a chamber with which is connected a tube j^1 leading to a compensator J^2 , for example, 105 of the character described in the applica- 110

tion of Richard D. Fay, Serial No. 238,839 filed June 8, 1918, or of any other character such that the distance of the sound travel between the diaphragms C, C¹ and the observer's ears may be adjusted so that the sound which strikes the diaphragm C will take as long to travel to the observer as the sound which strikes the diaphragm C¹, thus compensating for the difference in distance between the source of sound of C and C¹, respectively. J³, J³ are stethoscopic telephone ear-pieces which, being well known, need not be described in detail. Each is connected through the compensator and a tube j¹ with the chamber in one of the casings J¹.

In using this instrument the observer puts the ear-pieces in his ears and adjusts the ear-pieces until the sounds from both diaphragms C, C¹ reach his ears at the same instant. This form of my invention being adjustable is particularly adapted to cases where the sought-for sound may come from any one of a number of directions. By this means its direction may be determined.

Thus the indicating instrument, that is the instrument which conveys the intelligence to the observer, may be electrical or merely acoustical, and it will be understood by those skilled in the art that the equalization of the paths of travel from the source of sound to the observer may be arrived at in other ways than those described, the purpose of my invention being to provide means whereby the sound may arrive at the indicator from the source from a plurality of diaphragms or other receivers in phase, thus multiplying the effect upon the indicator. Sounds arriving at the receivers from directions other than that desired will not reach the indicator or the converging paths in phase and hence will interfere and more or less nullify each other. The length of the various paths for the sound may be determined by experiment or calculation in any given case according to the part of the ship in which the receivers are to be located and the direction from which the sound is to be expected. These paths should be of a non-compressible material such as fluid or a solid as with a compressible material such as a gas too much energy would be taken up in the compression of the gas and the result would be comparatively feeble, if effective at all.

Various modifications may be constructed which will come within my claims for I do not mean to restrict myself to the precise forms of construction shown and described.

While my invention is primarily intended for use on board ship, it may be otherwise installed, although described particularly with reference to ship use.

What I claim as my invention is:—

1. In a device for determining the direc-

tion of subaqueous sound signals, detecting means spaced substantially in a horizontal plane in the skin of a vessel, transmitting means, receiving means, said transmitting means connecting said detecting means to 70 said receiving means, the length of said transmitting means being proportioned so that only sounds from directly ahead of the vessel will be transmitted in phase to said receiver. 75

2. In a device for determining the direction of subaqueous sound signals, a plurality of detecting means spaced substantially in a horizontal plane in the skin of a vessel, a plurality of sound conducting paths 80 of a noncompressible medium, a single receiver, each of said detecting means being connected to said single receiver by the said sound conducting paths, the length of said conducting paths being proportioned so 85 that only sounds from directly ahead of the vessel will be transmitted in phase to said receiver.

3. In a device for determining the direction of subaqueous sound signals, a plurality of diaphragms spaced substantially in a horizontal plane in the skin of a vessel, a plurality of sound conducting tubes, said diaphragms each closing an end of a conducting tube, a receiver, a chamber, said 90 receiver being positioned in said chamber, the other end of said conducting tubes communicating with said chamber, a noncompressible sound conducting medium connecting said receiver with said diaphragms 95 through the conducting tubes, the length of said conducting tubes being proportioned so that only sounds from directly ahead of the vessel will be transmitted in phase to the receiver. 100

4. In a device for determining the direction of subaqueous sound signals, a plurality of diaphragms spaced substantially in a horizontal plane in the skin of a vessel, a plurality of sound conducting tubes, said diaphragms each closing an end of a conducting tube, a microphone, a chamber, said microphone being mounted on the wall of said chamber, the other end of said conducting tubes communicating with said 110 chamber, a noncompressible sound conducting medium sealed within said conducting tubes by said chamber and said diaphragms, said medium connecting said microphone with said diaphragms, the length of the 115 sound conducting tubes being proportioned so that only sounds from directly ahead of the vessel will be transmitted in phase to the microphone. 120

5. In a device for determining the direction of subaqueous sound signals, a plurality of receiving units mounted on the port and starboard side of a vessel, positioned so as to be screened from one another by the vessel itself, a plurality of diaphragms 125 130

spaced substantially in a horizontal plane in the skin of the vessel, a plurality of sound conducting tubes, said diaphragms each closing an end of a conducting tube,
5 a receiver, a chamber, said receiver being positioned in said chamber, the other end of said conducting tubes communicating with said chamber, a noncompressible sound conducting medium connecting said receiver with said diaphragms through the sound conducting tubes, the length of said conducting tubes being proportioned so that only sounds from directly ahead of the vessel will be transmitted in phase to the
10 receiver whereby the direction of the sound source may be determined by both port and starboard receivers or either receiver.
15 6. In a device for determining the direction of subaqueous sound signals, a plurality of tanks mounted on the port and starboard side of a vessel positioned so as to be screened from one another by the vessel itself, said tanks being filled with a noncompressible fluid, a plurality of diaphragms spaced substantially in a horizontal plane in the skin of the vessel within said tanks, a plurality of sound conducting tubes, said diaphragms each closing an end of a conducting tube, a microphone, a chamber, said microphone being mounted on the wall of said chamber, the other end of said conducting tubes communicating with said chamber, a second non-compressible sound conducting medium sealed within said conducting tubes by said chamber and said diaphragms, said second sound medium connecting said microphone with said diaphragms, the length of the sound conducting tubes being proportioned so that only sounds from directly ahead of the vessel will be transmitted in phase to the microphone whereby the direction of the sound source may be determined by both port and starboard microphones or by either microphone alone.

ROBERT L. WILLIAMS.
